INVENTOR
Gerard R. Marsico

UNITED STATES PATENT OFFICE.

GERARD R. MARSICO, OF BROOKLYN, NEW YORK.

SIGNAL.

1,306,493.

Specification of Letters Patent. Patented June 10, 1919.

Application filed June 28, 1918. Serial No. 242,445.

To all whom it may concern:

Be it known that I, GERARD R. MARSICO, a citizen of the United States, and resident of Brooklyn, in the county of Kings and 5 State of New York, have invented certain new and useful Improvements in Signals, of which the following is a specification.

My invention relates to audible signals and more particularly to what are known as 10 diaphragm horns, wherein pulsating movements are adapted to be set up in the diaphragm by means of a rotor or striker acting thereagainst.

Heretofore, horns of the above described 15 type have included a rotor, a ratchet wheel and detent, whereby motion of the rotor will be checked in one direction, and mechanism for advancing the detent against the ratchet wheel to place the rotor in action. 20 To the best of my knowledge, the detent mentioned is always yieldingly held in contact with the ratchet wheel and as a consequence thereof, undue friction and wear and tear are set up between the parts and 25 the efficiency of the structure is thereby seriously impaired, it being impossible through the production of such friction to obtain a maximum working action of the rotor against the diaphragm.

30 In my invention which I will fully describe hereinafter, I have provided a structure wherein the diaphragm is displaced in a manner whereby the emitted sounds will be of a clear pitch and greater magnitude to insure a loud quick and sharp signal of uniform intensity and in practice, I employ a heavy rotor, a revolving hanger, and means on the hanger adapted to be actuated by centrifugal action and engage with the 35 rotor at a point remote from the axis thereof and thereby augment the leverage force of said means against said rotor and thus accelerate pulsation of the diaphragm.

I more specifically provide a rotor having 45 an external striking surface adapted to coact with the anvil of a diaphragm and an internal ratchet surface, the latter coacting with centrifugally advanced dogs or detents which are movably mounted upon 50 a revolving hanger and adapted to be brought into positive contact with the ratchet surface when motion is transferred to the hanger.

Another object of the invention is to provide 55 a horn having its diaphragm provided with a fixed anvil and mechanism coacting

with the anvil to displace the diaphragm, the said mechanism including actuating means and all of which are mounted from a common support which is adjustable with 60 relation to the anvil whereby proper contact between the anvil and the diaphragm displacing means can be obtained always at the convenience of the user.

Another object of the invention is to provide 65 a horn including a diaphragm provided with an anvil, a ratchet provided with an external striking surface and an internal ratchet surface, a revolving hanger, and identical detents supported from the hanger 70 in coacting relation with the ratchet surface and reversibly arranged upon the hanger so that when the detents are worn at one side, their positions may be reversed to insure their proper contact with the ratchet 75 surface.

A still further object of the invention is to provide a horn having a diaphragm and a coacting rotor, the latter having an external striking surface and an internal 80 ratchet surface, the teeth of the latter being relatively broad and arranged to coact with detents which are provided with broad coacting surfaces arranged for impingement against the ratchet surface when the detents 85 are actively presented thereto.

A still further object of the invention is to provide a structure of the class specified which will be simple, strong and durable and which will consist of parts capable of 90 being readily separated from each other to permit of the substitution of new parts for worn ones or to otherwise enable access to be properly gained to any of the parts for any purpose whatsoever.

95 In the drawings:—

Figure 1 is a longitudinal section through a portion of the structure showing parts in full lines.

Fig. 2 is a section on line 2—2 of Fig. 1. 100

Fig. 3 is a section on line 3—3 of Fig. 1 with parts in elevation.

Fig. 4 is a vertical section through the rotor showing the detent hanger slightly separated therefrom.

Fig. 5 is a side view of the detent hanger.

Fig. 6 is an enlarged side view of one of the detents.

Fig. 7 is a section taken substantially on line 7—7 of Fig. 3.

Fig. 8 is a perspective view of the spring.

Fig. 9 is a side view of a horn showing a

slightly modified form of the invention, parts being broken away in order to fully disclose the construction.

Fig. 10 is a plan view of the rotor support of the modified form shown in Fig. 9.

In carrying the invention into practice, use is made of a casing 15 including an amplifier 16 and a diaphragm 17, the latter having an anvil 18 of any approved well known construction. Located within the casing 15 is a rotor 19 which is supported to revolve upon an axle 20 which is mounted in a support 21.

The rotor 19 consists preferably of a heavy wheel of case hardened steel and it is provided with an external striking surface 22 and an internal ratchet surface 23, the teeth of said ratchet surface being of substantially V shaped formation and the same are separated from each other at relatively great intervals by intervening spaces 24 and disposed at a relatively remote distance from said axle 20. The teeth are relatively broad as clearly shown in Fig. 4 and they lie parallel with the center or axis of the rotor for a purpose to be hereinafter fully explained. The rotor is provided with a central opening 25 which freely receives the central portion of the axle 20, said axle having reduced ends 27 and 28 which are respectively mounted in the side branches 29 and 30 of the support 21. This support has its branches 29 and 30 provided with annular extensions 32 which are secured by fastenings 33 to a plate 34. This plate is mounted upon screws 35 at the crown 36 of the casing 15 and as illustrated, these screws are adjustable in the plate in order that the latter may be slightly separated from the crown 36 to permit of movement of the support in the direction of the diaphragm so as to regulate the pressure of the striker surface 22 against its coacting anvil 18 of the diaphragm. In order to permit of a proper retention of the selected adjustment of the support, I provide a regulating screw 37 the same being adjustably mounted upon the crown 36 and arranged in free contact with the plate 34 so as to hold the latter in a relatively fixed position.

The axle 20 is provided with a small gear wheel 38 and adjacent to said wheel and fixed to the axle is a relatively longer hanger 39 having one or any suitable number of pins 40 which project into the open side 41 of the rotor. These pins terminate approximately at the closed side 42 of the rotor and as illustrated they are freely extended through apertures 43 in detents 44. These detents are each provided with a relatively broad flat surface 45 which is adapted to come in flat contact with the next adjacent tooth of the described ratchet surface 23. By arranging the broad flat surfaces of the

ratchet teeth parallel with the axis of the rotor and providing the correspondingly formed flat surfaces 45 on the detents, a substantial mating contact will be established between the parts when it is desired to cause the rotor to become temporarily fixed to the axle. As a result of this arrangement, lost motion between the parts will be avoided and a positive action established at all times. The branches 29 and 30 of the support are relatively separable as stated, in order that the rotor and in fact all of the several working parts of the mechanism can be removed when desired and the positions of the detents reversed upon their supporting pins 40 in order to compensate for possible wear between the surfaces 45 and the broad flat surfaces of the teeth 23.

The gear wheel 38 is in constant mesh with a power transmitting gear 46 which is mounted upon an axle 47 journaled in the branches 29 and 30 as shown in Fig. 3. This axle is provided with a small gear wheel 48 which meshes with the teeth of an actuator 49. This actuator is in the form of a sliding rod and it is provided with a cap 50 upon its exposed end in order that it may be conveniently manipulated by hand. Said actuator is mounted to slide in a guide 51 secured to the branch 29 of the support 21 and as shown, the actuator is provided with an opening 52 in which the hooked end 53 of a spring 54 is removably engaged. This hooked end of the spring extends from a branch 55 of said spring and as shown in Fig. 7, said branch is freely slidable in a slot 56 formed in the branch 29 of the support 21. The opposite terminal of the spring is angularly offset at 57 and is removably engaged in a downwardly and inwardly extending opening 58 in said branch 29 of the support. In this manner the spring is freely removable from the operating parts of the mechanism to permit the actuator 49 to be entirely withdrawn from the casing if desired. The office of this spring is to normally hold the actuator in an active extended position as shown in Figs. 1 and 2 of the drawings and it serves to permit of an immediate return of the actuator to its normal position when pressure of the hand is removed from the cap 50. It further functions to cause the gear trains between the actuator and the axle 26 to reverse its operation when pressure of the hand is released from the actuator so that all of the several instrumentalities will properly assume their starting positions after motion in one direction has been set up in the rotor.

The rotor is provided with a central detent support 59 which operates to limit the gravitational movements of the detents in the direction of the axle 26. This is deemed properly essential in order to permit the de-

tents to be positively moved centrifugally when rotary motion in one direction is imparted to the hanger 39.

In operation, pressure in a downward direction is applied to the actuator 49 which in turn, revolves the axle 26 in the direction of the arrow shown in Fig. 1. In so doing, the detents 44 are moved by centrifugal action into coacting contact with the teeth 23 of the rotor and the latter then becomes a fixed part temporarily of the axle and both are made to rotate together in the same direction. When the downward movement of the actuator is released the latter is elevated 10 or returned to its normal position under the action of the spring 54. The gear train between the actuator and the axle 26 is then affected so as to revolve the axle in an opposite direction and thereby render the detents inactive. The rotor then continues to revolve by inertia in the presence of the anvil 18 of the diaphragm. The parts are combined with a regard to accomplishing a perfect balance of the several instrumentalities 20 so that a high measure of efficiency is obtained and sounds of a high amplitude and of a long duration, set up.

In the form of the invention shown in Figs. 9 and 10, the actuator 49 is arranged 30 in direct contact with a small gear wheel 60 upon an axle 61. Aside from this specific arrangement the essential parts of the mechanism are identical with those in the previously described embodiment.

From the foregoing, it is thought that the construction, operation and many advantages of the herein described invention will be apparent to those skilled in the art without further description; and it will be understood that various changes in the size, shape, proportion, and minor details of construction may be resorted to without departing from the spirit or sacrificing any of the advantages of the invention. For instance, 40 I would not desire to limit myself to the particular actuating mechanism herein shown for transferring motion to the axle 27 as many ways might be substituted for the means suggested herein, although I find 50 the present means practical and fully appropriate in every respect.

What is claimed as new is:—

1. In a device of the class described, a vibratory member, a rotor coacting with said member to vibrate the same, an annular interior clutch surface on the rotor adjacent the periphery thereof, a movable hanger, clutch devices on the hanger adapted on movement of the latter to engage with said 55 annular clutch surface, and means for transmitting motion to said hanger to advance

the clutch devices thereof into driving engagement with said annular clutch surface.

2. In a signal adapted to be sounded by the rotation of a rotor, an interior ratchet 65 surface on the rotor near the outer periphery thereof and concentric with the latter, a rotatable member mounted concentrically with the rotor and independently thereof, detents on the said rotatable member adapted 70 when the latter is rotated to move into engagement with said ratchet surface to lock the rotor and said member together, and means for rotating said rotatable member at high speed. 75

3. In a device of the class described, a vibratory member, a rotor engaged with said member and adapted to actuate the same when rotating, an annular interior ratchet surface on said rotor near the outer periphery of the rotor and concentric with the same, a hanger movable independently of the rotor and concentric therewith, the said hanger comprising radial arms, detents carried by said arms and adapted to engage 80 with the said ratchet surface, and means for rotating said hanger. 85

4. In a device of the class described, a vibratory member, a support, an axle upon said support, a rotor rotatably supported 90 upon said axle and operatively engaged with said vibratory member, an annular interior ratchet surface on said rotor near the outer periphery thereof, a hanger secured upon said axle and comprising radial arms, de- 95 tents near the outer ends of said arms adapted to engage with said ratchet surface and to lock the hanger and rotor together, a relatively small pinion affixed to said axle, a large gear in mesh with said pinion, a 100 small gear affixed to the said large gear, a rack plunger in mesh with said small gear, and means for holding the plunger at the limit of its movement in one direction.

5. In a device of the class described, a 105 vibratory member, a support, an axle upon said support, a relatively large rotor loosely mounted upon said axle, and having its periphery operatively engaged with said member, one side of said rotor being cut 110 away to provide inner and outer concentric surfaces, a hanger secured to said axle and comprising radial arms, pivoted elements at the ends of said arms and disposed in the cut away portion of said rotor, the said ele- 115 ments limited in their inward swinging movement by said inner surface and adapted to engage the said outer surface when swung outwardly, and means for rotating said axle.

In testimony whereof I affix my signature. 120

GERARD R. MARSICO.
